FORMING APPARATUS

August R. Bringewald, North Babylon, N.Y., assignor to Republic Aviation Corporation, Farmingdale, N.Y., a corporation of Delaware

Application June 22, 1955, Serial No. 517,141

3 Claims. (Cl. 113—44)

This invention relates in general to forming apparatus and more particularly to a forming apparatus or press for forming sheet metal or like materials.

Among other features desired in forming apparatus or presses for forming sheet metal is the ability to perform varied forming operations, as well as compactness so that the press occupies a minimum of space. Moreover, it is desirable that the forming apparatus be so constructed and arranged that it can be readily converted to perform different types of forming with a minimum of interference with production.

Therefore, among other objects the present invention contemplates a press or forming apparatus having the capacity of performing both simple and multiple forming operations, that is relatively compact and which can be converted for different forming operations without completely shutting down the press so that a minimum of production is lost during such conversions.

To these ends, the forming apparatus contemplated herein comprises a sectional bed and head movably mounted thereon for selective individual cooperation with each bed-section to combine therewith to create a complete forming unit adapted to perform a particular type of forming operation. Thus, the bed-sections are constructed and arranged so that one may be selected to individually cooperate with the head to perform one type of forming operation such as press-block forming, blanking, flanging etc., while a second section may be selected to cooperate with the head to perform another type of forming operation such as deep drawing. In short, the instant forming press is capable of various types of forming operations merely by selecting the bed section appropriate to a particular forming operation and adjusting the head, which is common to all types of forming, to cooperate with the selected bed section.

With the above and other objects in view, as will be apparent, this invention consists in the construction, combination and arrangement of parts all as hereinafter more fully described, claimed and illustrated in the accompanying drawings wherein:

Fig. 1 is a plan view of a forming press constructed in accordance with the present invention;

Fig. 2 is a front elevation thereof;

Fig. 3 is a longitudinal section taken along line 3—3 of Fig. 1 showing the head moved to the position where it coacts with a bed-section adapted for deep drawing;

Fig. 4 is a transverse section taken along line 4—4 of Fig. 1 where the head is illustrated in position to cooperate with a bed-section, adapted for flanging or press block forming;

Fig. 5 is a perspective partially in section of the frame for supporting the rubber forming pad and diaphragm of the instant press; and

Fig. 6 is a fragmentary view in section of a detent assembly used in maintaining the frame of the pad and diaphragm in its position in the head.

2

Referring now to the drawings, in Figs. 1, 2 and 3, 10 designates the sectional bed of the sheet metal forming press contemplated herein comprising a plurality of individual bed-sections, in this instance, three sections 5 11, 12 and 13 being shown, that are aligned in end-to-end relationship to form longitudinal continuations of each other and fixedly secured together by any conventional means (not shown). While only three bed-sections have been illustrated and described, it is to be understood that any number of bed-sections may be employed as desired. The bed 10 also may be a single unitary structure suitably divided into individual bed-sections.

The bed-section 11 comprises a body 14 that is substantially rectangular in both longitudinal and transverse section. At its upper edge portions, the body 14 is provided with longitudinal side walls 15 and 16 that extend along the full length of the section 11 at opposite sides, thereof, and with oppositely disposed transverse end walls 17 and 18 that extend transversely across its opposite ends. These transverse end walls 17 and 18 terminate short of the longitudinal walls 15 and 16 to create openings adjacent the walls 15 and 16 to accommodate the adjustment of the head longitudinally of the bed 10 as will be seen. For purposes that will herein-after be apparent, the end wall 17, which forms one extremity of the sectional bed 10, is twice the thickness of the opposite end wall 18. The bed-sections 12 and 13 are generally the same in construction and arrangement 20 as the bed-section 11, the former comprising a body 19 having longitudinal walls 20 and 21 and transverse walls 22 and 23, and the latter a body 24 having longitudinal walls 25 and 26 and transverse walls 27 and 28. As shown in Fig. 1, the walls 15, 20 and 25 form longitudinal continuations of each other along one side of the sectional bed 10, while the walls 16, 21 and 26 are similarly disposed along the opposite side of the bed 10. Further, the transverse end walls 18 and 22 as well as the 25 transverse end walls 23 and 27 adjoin each other, while 30 the transverse end walls 17 and 28 constitute the opposite extremities of the sectional bed 10 and as above noted are substantially twice as thick as the other transverse walls.

A head, generally indicated as 29, is slidably mounted 35 for longitudinal movement on the sectional bed 10 so that it can be brought into vertical alignment individually with each bed-section 11, 12 and 13 with which it combines to comprise a forming unit. More particularly, the bed-section 11 is provided at each longitudinal side 40 with a vertical open slot 30 which communicates at its lower end with a track 31. Each track 31 is substantially triangular in cross-section and is formed with its base portion disposed across and normal to the adjacent end of its associated slot 30 thereby creating divergent shoulders 31' at the inner end of the open slot. The slots 30 and tracks 31 extend along each side of the bed-section 11 for the entire length of the body 14. The bed-sections 12 and 13 are similarly provided with vertical slots 32 and 33 respectively which communicate 45 with tracks (not shown) similar to the tracks 31. When the bed-sections 11, 12 and 13 are aligned and secured together as above described, the slots 30, 32 and 33 and their respective tracks align to form a continuous slot and track along each longitudinal side of the sectional bed 10 and for its entire length.

The head 29 comprises a hollow, semi-cylindrical yoke 36 having depending opposed, parallel sides 37, each of which is enlarged to form a guide 38 shaped to agree with the track 31 and operate below and against the shoulders 31'. As shown in Fig. 4, the sides 37 and the guides 38 of the yoke 36 are adapted to be slidably received in the

slots 30—32—33 and their tracks, to the end that the head 29 is slidably supported for reciprocating movement along the entire length of the bed-section 10. Moreover, due to the engagement of the base portions of the guides 38 and the tracks, vertical displacement of the head 29 relative to the sectional bed 10 is prevented.

The yoke 36 is of such a length that when it is positioned over or aligned vertically with one of the bed-sections, it extends longitudinally over and encompasses that bed-section as well as the adjoining end or transverse wall of the next adjacent bed-section. Thus, when the head 29 is aligned with bed-section 13, as shown in Fig. 3, the yoke 36 extends, at one extremity, over the end wall 28 of the bed-section 13 while its opposite extremity covers both the end wall 27 of the bed-section 13 and the adjoining end wall 23 of the next adjacent bed-section 12.

In addition to the foregoing means for supporting the head 29 for movement longitudinally of the sectional bed 10, each longitudinal side of the sectional bed 10 is provided with a continuous, coextensive rail 39. As shown in Figs. 1 and 4, one rail 39 is secured to, or formed integrally with, the upper edges of the longitudinal side walls 15, 20 and 25 while the other is similarly disposed on the upper edges of the opposed longitudinal side walls 16, 21 and 26. Each side of the yoke 36 carries a housing 49 in which is rotatably supported a plurality of grooved wheels 41 that engage the adjacent rail 39. Thus, the rails 39 and the wheels 41 form an additional means for supporting the head 29 for longitudinal movement with respect to the sectional bed 10 that facilitates this movement of the head 29.

To provide means for moving the head 29 along the sectional bed 10 and for selectively aligning it with the bed-sections 11, 12 and 13, an electric motor 42 is suitably mounted on one of the housings 40 and adjacent one end thereof. The shaft 43 of the motor 42 extends vertically and downwardly and is provided at its lower extremity with a worm 44 that engages a worm-gear 45 mounted on the side of the adjacent grooved wheel 41. The motor 42 is connected into a conventional electrical circuit including a power source and a control switch (not shown) whereby the motor 42 is actuated to drive the shaft 43, worm 44 and worm-gear 45 so as to move the head 29 along the sectional bed 10. If desired, the grooved wheels 41 may be interconnected by a conventional chain and sprocket drive (not shown). While only one motor 42 is shown, a second motor may be similarly mounted on the opposite side of the yoke 36 and operatively connected to the wheels 41 on that side, as aforesaid, thereby providing balanced driving power for the head.

In order to control the movement of the head 29 along the sectional bed 10, so that it may be selectively aligned with any one of the bed-sections, a conventional limit switch 46, having a contact button 47, is fixedly secured to the upper portion of the wall 15 of the bed-section 11 at, or adjacent to, the end wall 17 with its contact button 47 facing in the direction of the opposite end of the sectional bed 10, or to the right as viewed in Fig. 1. Another conventional limit switch 48 is fixedly mounted at the opposite extremity of the sectional bed 10, i.e. to the upper part of the side wall 26 of the bed-section 13 at, or adjacent the end wall 28, with its contact button 49 facing in the direction of, and in alignment with, the contact button 47, i.e. to the left as shown in Fig. 1. A pair of conventional limit switches 50 and 51, having contact buttons 52 and 53 respectively, are pivotally mounted to the upper part of the longitudinal side walls 15 and 25 of the bed-sections 11 and 13. The switch 50 is disposed at or adjacent the end wall 18 with its contact button 52 facing in the same direction as the contact button 47 of the limit switch 46 and the switch 51 at or adjacent the end wall 27 with its button 53 facing in the same direction as the contact 49 of the limit switch 48. Each of the limit switches 50 and 51 is pivotally mounted

to their respective side walls in such a manner that it may be swung between a raised operative position where it is aligned with the fixed limit switches 46 and 48 and a lowered inoperative position where it lies along the outer face of the coating side wall. The limit switches 46, 48, 50 and 51 are conventionally connected to the electrical circuit of the motor 42 in such a manner that when the motor 42 is running, pressure applied to the contact buttons 47, 49, 51 or 52, opens the motor circuit and stops the operation of motor 42.

In order to apply operative pressure to the buttons 47 and 52, the head 29 is provided at one extremity with an arm 54 that projects from the housing 40 to which it is attached by a bracket 55. Hence, as the head 29 moves relative to the bed 10, the projecting arm 54 engages the contact button 47 of the limit switch 46 or the contact button 52 of the limit switch 50 when the latter is in its raised position. A second contact arm 56 is similarly mounted by a bracket 57 on the housing 40 at the opposite extremity of the head 29 and disposed, so as to engage with the contact button 53, when the switch 51 is in its raised position, and the contact 49 of the switch 48.

Due to the foregoing arrangement, when the head 29 is positioned in alignment with the bed-section 11, as shown in Figs. 1 and 2, and it is desired to move it into alignment with the bed-section 12, the limit switch 50 is moved to its lowered inoperative position and the limit switch 51 to its raised operative position. The control switch of the motor circuit (not shown) is then closed to initiate the operation of the motor 42 in a direction whereby its shaft 43, the worm 44 and worm-gear 45 drive the grooved wheel 41 to move the head 29 on the rails 39 to the right or toward the bed-section 12. Since the limit switch 50 is in its lowered position, it does not lie in the path of movement of either of the contact arms 54 and 56. However, when the contact arm 56 engages and depresses the button 53 of the limit switch 51, the motor circuit is opened, as aforesaid, and the operation of the motor 42 stops. The relative positions of the limit switch 51 and contact arm 56 are such that when the switch is operated to open the motor circuit and stop the motor 42, the head 29 is aligned with, i.e. positioned vertically over, the bed-section 12. To move the head 29 further to the right for alignment with the bed-section 13, the limit switch 51 is swung to its lowered position and the control switch actuated to operate the motor 42 in the same direction as above set forth. In response to this operation of the motor 42, the head 29 is moved to the right until the contact arm 56 depresses the button 49 of limit switch 48 causing the motor 42 to stop. The contact arm 56 and limit switch 48 are so disposed that when the arm actuates the button 49 of the switch, thereby stopping the motor 42, the head 29 is then disposed over the bed-section 13. The head 29 is moved in the opposite direction, i.e. from right to left, as viewed in Fig. 1, by revising the operation of the motor 42. In this instance, however, the limit switch 51 is swung to its lowered position and the limit switch 50 to its raised position. When the contact arm 54 depresses the button 52 of the limit switch 50, the motor circuit is opened and the motor 42 stopped. At this time, the head 29 is vertically positioned over the bed-section 12. Further movement of the head 29 to the left (Fig. 1) is accomplished by lowering the limit switch 50 and continuing the reverse operation of the motor 42 and the associated driving mechanism to move the head 29 to the left. When the arm 54 contacts the button 47 of switch 46, the motor circuit is opened and the motor 42 arrested with the head 29 then disposed over the bed-section 11. For movement of the head 29 from one extremity to the other of the sectional bed 10, i.e. from bed-section 11, or vice versa, the intermediate limit switches 50 and 51 are both swung to their lowered inoperative positions out of the path of the arms 54 and 56. Whereupon the head 29

is moved in either direction until the contact arm 54 or contact arm 56 contacts the button 47 or 49, as the case may be, to arrest the motor 42 and hence the movement of the head 29 along the sectional bed 10.

As shown, particularly in Figs. 3 and 4, the yoke 36 has fixedly mounted therein, by any conventional means (not shown), a filler block 60 having a centrally disposed cavity 61 formed therein for deep-drawing forming operations. The filler block 60 is provided, at its opposite longitudinal ends, with depending vertical flanges 62 and 63 that are so constructed and arranged that when the head 29 is aligned with a bed-section, they form vertical continuations of the transverse end walls of the bed-section then associated with the head 29. For example, when the head 29 is aligned with the bed-section 13, as shown in Fig. 3, the flange 62 is disposed over and forms a continuation of the end walls 23 and 27 while the flange 63 is disposed over and forms a continuation of the end wall 28. Because of this arrangement a forming chamber 64 is produced between the head 29 and the bed-section 13 defined at one end by the inner surfaces of the flange 62 and end wall 27 and at the opposite end by the inner surfaces of the flange 63 and end wall 28. The sides of the forming chamber 64 are defined by the inner surfaces of the adjacent portions of the depending sides 37 of the yoke 36, while its upper and lower limits are defined, respectively, by the bottom surface 65 of the filler block 60 and the upper surface 24' of the body 24.

Similarly, when the head 29 is associated with either the bed-section 12 or the bed-section 11, the forming chamber 64 is produced as above described except that in the first instance, its lower limit is defined by the upper surface 19' of the body 19, and in the second instance by the upper surface 14' of the body 14. Due to this construction, the upper surfaces 14', 19' and 24' of the bed-sections 11, 12 and 13 respectively, serve as tables upon which one or more press-block forming or blanking dies may be mounted or positioned, such as the die or press-block 66 shown positioned on the table 14' of the bed-section 11 in Fig. 3.

The bed-sections 11 and 12 are each adapted to cooperate with the head 29 for one type of forming such as press-block, flanging or blanking and therefore their respective tables 14' and 19' are relatively smooth, flat surfaces. The bed-section 13, however, is not only adapted for flanging, blanking and press-block forming as aforesaid, but also is capable of forming hollow bodies as by deep-drawing. To these ends, the body 24 of the bed-section 13 is provided with a centrally disposed, cylindrical bore 67 which serves as a cylinder for a hydraulic ram 68. The ram 68 has a piston 69 suitably mounted to its lower end. This piston 69 slidably engages the wall of the cylinder 67, while the upper end of the ram 68 has a die 70, of any selected shape or size, secured thereto for reception in and cooperation with the cavity 61 in the filler block 60 during deep-drawing operations. A conventional hydraulic system including control means therefor (not shown) is connected to the cylinder 67 whereby a hydraulic fluid under pressure is selectively delivered thereto to either extend the ram 68 therefrom and thereby raise the die 70 in the direction of the cavity 61 or to retract the ram 68 into the cylinder 67 to lower the die 70 to the position shown in Fig. 3, where its bottom rests upon the table 24'.

In addition, the body 24 is also provided with a rectangular piston chamber or cylinder 71 that surrounds the cylinder 67. A plurality of vertical openings 72 extend between the piston chamber 71 and the table 24'. Each opening 72 has slidably mounted therein a lifter pin 73. At their lower ends, the lifter pins 73 contact or engage the upper surface of a rectangular piston 74 that is mounted for vertical movements within the piston chamber 71. The lifter pins 73 extend only partially into the openings 72 so that a pressure pin 75

75 may be inserted through the upper extremity of each, or any selected number of the openings 72, to rest upon the upper end of the lifter pin 73 mounted therein. At their upper ends, the pressure pins 75 are constructed and arranged to support a pressure plate 76 having a central opening 77 therein to permit the passage of the male die 70. The pins 75 are removably mounted within the openings 72 to the end that any selected number may be employed depending upon the particular size and shape of the pressure plate 76 as determined by the configuration of the workpiece 79. As in the instance of the cylinder 67, piston chamber 71 is connected to a conventional hydraulic system having a control means (not shown) whereby a hydraulic fluid under pressure may be selectively delivered to the chamber 71 to either raise or lower the piston 74 and thereby raise or lower the pressure plate 76 supported by the pins 75 and their respective underlying lifter pins 73.

As set forth, when the head 29 is aligned with either 20 of the bed-sections 11, 12 or 13, the head 29 and associated bed-section cooperate to define a forming chamber 64. To provide means for forming a sheet metal workpiece disposed within the forming chamber 64, e.g. a workpiece 78 positioned on a die block 66 or a workpiece 79 positioned on the pressure plate 76, a forming assembly 80 (Fig. 5) is mounted within the head 29. This assembly 80 is constructed and arranged either for movement within the chamber 64 and relative to the head 29 or it may be locked within the head 29 against 30 such movement, depending upon the type of forming to be accomplished.

More particularly, the forming assembly 80 comprises a rectangular frame 81 the outer sides 82 of which are adapted to fit within the head 29 and slidably engage 35 the inner surfaces of the flanges 62 and 63 of the filler block 60 and of the depending sides 37 of the yoke 36, as well as fit within the inner surfaces of the side and end walls of the associated bed-sections. The sides of the frame 81 are U-shaped in section, to establish an open, rectangular groove 83 that extends inwardly from the inner faces 84 of the sides of the frame 81 to receive and retain the outer or marginal edge of a resilient forming pad 85. A molding 86 corresponding in shape and size to the frame 81, having a vertical flange 87 formed at its outer edges, is fixedly secured to the upper surface of the frame 81 with its flange 87 in alignment with and forming a continuation of the outer sides 82 of the frame 81. For reasons that will hereafter be apparent, the upper surface of the resilient 45 forming pad 85 is covered and protected by a deformable, elastic diaphragm 88 fabricated from any suitable material having good stretching properties, and which is impervious to oil or other hydraulic fluids used in forming operations. The diaphragm 88 is provided, at its 50 margin or outer edge, with an upstanding feather seal or lip 89 having a relatively flat outer surface 89' and is secured in any suitable manner to the molding 86. If desired, the diaphragm 88 may be cemented or otherwise joined to the upper surface of the resilient forming 55 pad 85.

Due to this construction and arrangement the forming assembly 80 is adapted to move vertically within the chamber 64. In order to guide the forming assembly 80 during such vertical movement, a guide rod 90 is 60 mounted in a vertical position at each of the four corners of the frame 81 to extend upwardly into and slidably engage aligned openings 91 and 92 formed in the block 60 and the yoke 36 respectively. These guide rods 90 may be mounted on the forming assembly 80 in any suitable manner, for example, the lower ends thereof 65 may be threaded to engage threaded sockets (not shown) in the molding 86 and frame 81.

To secure or lock the forming assembly 80 within the head 29, a groove 93 is formed in the outer faces of the sides 82 of the frame 81 to be engaged by a plurality

of detent assemblies 94 mounted in the flanges 62 and 63 of the filler block 60 and the sides 37 of the yoke 36. Since these detent assemblies 94 are each of the same construction, only one of them disposed in the flange 63 is described.

This detent assembly 94 comprises an open socket 95 formed in the flange 63 with its open end communicating with the chamber 64. A retaining ring 96 having a central opening 97 is mounted in a recess in the flange 63 about the open end of the socket 95. The ring 96 is so mounted that its outer surface 96' is flush with the surrounding surface of the flange 63 and its central opening 97 is concentrically disposed relative to the socket 95. A spherical member or ball 98 is slidably mounted in the socket 95, inwardly of the retaining ring 96 and a spring 99 operates between the closed end of the socket 95 and the ball 98 to project the latter partially through the opening 97 of the ring 96. When the ball 98 is thus seated it extends, in part, through the central opening 97 of the ring 96 and into the chamber 64. Because of the foregoing arrangement, when the groove 93 in the sides 82 of the frame 81 aligns with the ball 98, the part of the latter projecting into the chamber 64 seats within the groove 93 to lock or secure the frame 81 and hence the forming assembly 80 into the head 29. However, the force exerted by the spring 99 on the ball 98 is such that when a predetermined force is exerted on the upper surface of the forming assembly 80 the spring 99 is overcome and the ball 98 is pushed or moved into the socket 95 by its coaction with sides 82 defining the groove 93. As a result, the ball 98 is disengaged from the groove 93 thus freeing the forming assembly 80 for vertical movement downwardly and relative to the head 29 and block 60 within the chamber 64.

The yoke 36 and block 60 are provided with registered passages 100 and 101 respectively that communicate the chamber 64, through the female die cavity 61, with the exterior of the head 29. The passage 100 is connected through suitable conduit means with a conventional hydraulic system having control means (not shown) whereby a hydraulic fluid under pressure may be delivered to or withdrawn from the upper portion of the chamber 64, i.e. that part of the chamber 64 above the forming assembly 80. When hydraulic fluid under pressure is admitted into the chamber 64 from the hydraulic system through the passages 100 and 101, it is effective on the upper surface of the forming assembly 80, i.e. the diaphragm 88, to produce a force thereon of sufficient magnitude to unlock the forming assembly 80 from the detent assemblies 94 as aforesaid and to move it downwardly toward the table of the bed-section with which the head 29 is then associated. Thus, when the head 29 is associated or aligned with the bed-section 11 as aforesaid, to press-form the workpiece 78 positioned on the die 66, the delivery of hydraulic fluid under pressure through the conduits 100 and 101 into the upper part of the chamber 64 unlocks the forming assembly 80 and moves it toward the table 14'. The forming assembly 80 moves downwardly until its frame 81 engages a seat 102 disposed within a recess formed in the margin of the table 14'. To prevent damage to the pad 85, the inner surface 103 of the seat 102 against which the working surface of the forming pad 85 is pressed by the hydraulic fluid, is provided with a curved or (O-gee) surface. The hydraulic pressure on the diaphragm 88 and the resilient forming pad 85 produces a force that presses or conforms the workpiece 78 with the die block 66.

When the forming assembly 80 is positioned within the seat 102 as aforesaid, the walls 82 of the frame 81 and flange 87 of the molding 86 are disposed across the space between the bottom surfaces of the flanges 62 and 63 of the block 60 and the associated surfaces of the end walls 17 and 18—22. Moreover, the pressure of hy-

draulic fluid is effective against the feather seal 89 to press its outer surface 89' into sealing contact with the adjacent inner surfaces of the flanges 62 and 63 of the block 60 and the side walls 37 of the yoke 36. Thus, any leakage of the hydraulic fluid from the chamber 64 is prevented.

In order to raise the forming assembly 80 into its locked position in the head 29, after the forming of the workpiece 78, each of the four corners of the seat 102 is pierced by a vertical opening 104 that registers with a vertical opening 105 formed in the body 14. The lower end of the opening 105 terminates in a piston chamber 106 in which a piston 107 is mounted for vertical reciprocation. A lifter pin 108 slidably mounted in each of the registered openings 104 and 105 engages at its lower end the upper surface of the associated piston 107. A spring 109 is interposed between the bottom of the piston chamber 106 and the piston 107 to exert a force against the piston 107 to move it and its associated lifter pin 108 upwardly to abut the upper end of the pin 108 against the frame 81. The length of the lifter pins 108 and the combined forces of the springs 109 are such that when the hydraulic fluid is withdrawn from the upper part of chamber 64 upon the completion of the forming operation on the workpiece 78, the forming assembly 80 is raised or moved vertically upward within the chamber 64 to position the peripheral groove 93 formed in the outer face 82 of the frame 81 in alignment with the balls 98 of the detent assemblies 94. As a result, the forming assembly 80 is returned to its locked or secured position within the head 29 so as to travel therewith when it moves longitudinally on sectional bed 10. Furthermore, the length of the lifter pins 108 is such that when they are fully extended, as aforesaid, the upper extremities thereof are in the plane of the upper surfaces of the side walls 17 and 18, and hence they do not interfere with longitudinal movements of the head 29 on the sectional bed 10.

The bed-section 12 is similarly constructed, having a rectangular seat 110 for the reception of the frame 81 of the forming assembly 80. Four lifter pins 111, each of which is slidably mounted within registered openings formed in the seat 110 and body 19, and which abut or contact a piston 112 at one of their ends mounted for vertical movement within a chamber 113 and the frame 81 at their other ends. A spring 114 is operative against the piston 112 to raise it and its associated lifter pin 111. The bed-section 13 is also provided with a rectangular seat 115 to receive the frame 81, four lifter pins 116 slidably mounted in aligned openings in the seat 115 and body 24 each engaging a piston 117 slidably within a chamber 118, and a spring 119 operative against the piston 117.

As above described, the bed-section 13 cooperates with head 29 for deep drawing operations. For this type of forming, the hydraulic fluid is withdrawn from the upper part of the chamber 64, or the pressure thereon is relieved so that it may flow outwardly through the passages 101 and 100. The hydraulic system connected to the rectangular piston chamber 71 is then operated to deliver fluid under pressure thereto so that the piston 74 is moved upwards in the chamber 71. This upward movement of the piston 74 which raises these pins 73 and 75, the pressure plate 76 carried by the upper ends of the pins 75 and the workpiece 79 supported on the pressure plate 76, is continued until the workpiece 79 rests flush against the lower surface of the forming pad 85 to raise it and the diaphragm 88 until the latter engages or bears against the lower surface of the die block. Thus, the workpiece 79 and the adjacent portion of the forming pad 85 and diaphragm 88 are clamped between the pressure plate 76 and the adjacent face 65 of the block 60. When the desired clamping pressure is attained, the control means of the hydraulic system is actuated to stop the delivery of fluid to the chamber 71 and to hold the pressure then imposed upon the fluid.

The hydraulic system connected to the cylinder 67 is then operated to deliver fluid under pressure thereto to extend the ram 68 from the cylinder 67. As a result, the male die 70 moves upwardly through the opening 77 in the pressure plate 76 and into engagement with the lower surface of the workpiece 79. The continued upward movement of the ram 68 forces the workpiece 79 together with the diaphragm 88 and pad 85 into the cavity 61 of the block 60 to form or deep-draw the workpiece 79 into conformity with the die 70. Upon the completion of the forming of the workpiece 79, the control means of the hydraulic system is reversed to retract the ram 68 into the cylinder 67. As the male die 70 moves out of the cavity 61, the pad 85 serves to eject the formed workpiece 79 from the cavity 61.

If it is desired, the cavity 61 may have mounted there-in an additional rubber pad that assists in the deep-drawing operations.

The bed-section 13 is also adapted to cooperate with the head 29 in the same manner as the bed-sections 11 and 12 in performing press-block, flanging or blanking operations. In this instance, however, the pins 75 are removed from their co-acting openings 72 and the die 70 from the ram 68. The upper ends of the openings 72 and cylinder 67 are then closed by any suitable means (not shown) to provide a flat and unbroken surface for the table 24' upon which one or more press-block, flanging or blanking dies may be positioned. In the event the die 70 is suitable for use in the selected type of forming operation, e.g. the die 70 may be used for press-block forming, it may be left in position on the ram 68 or removed therefrom and positioned with other dies on the table 24'. Thereafter, workpieces may be formed on these dies in the same manner as when the head 29 cooperates with the bed-sections 11 and 12 in these types of forming operations.

Having thus described the details of construction and operation of the instant forming apparatus, it will be apparent that the several objects hereinbefore set forth have been accomplished. Thus, the forming press contemplated herein is capable of performing varied and different forming operations and is compact in construction and arrangement so as to occupy a minimum of space. Moreover, since the die or dies of one or more of the bed-sections may be changed without stopping the operation of the remaining bed-section, it is clear that some sections of the press may be converted for different forming operations while the remaining section or sections continue productive operations.

What is claimed is:

1. In apparatus for forming sheet metal workpieces, the combination with a stationary continuous bed, of means dividing said bed into a plurality of aligned and individual bed-sections each having a recessed portion, a forming head, continuous tracks carried by and disposed at the sides of said bed, means carried by said head and engaging said tracks for mounting said head on the bed for movement relative to and successively over all of said bed-sections and also cooperating with said tracks for restraining said head from movement normal to said bed, driving means for moving said head relative to said bed and for automatically and fixedly aligning it with any selected one of its sections, said head having a recessed portion adapted to cooperate with the recessed portion of the bed-section aligned therewith to define a forming chamber, a forming assembly carried by the recessed portion of said head and mounted to slide in both said recessed portions of said forming chamber, means for releasably securing said forming assembly against movement within the recessed portion of said

head, and pressure means for releasing said forming assembly from said securing means and moving it within said forming chamber to form a workpiece positioned in said forming chamber.

5 2. In a metal forming apparatus, the combination with a stationary continuous bed, of partitions dividing said bed into a plurality of individual and relatively independent bed-sections, a head, means carried in part by said bed and in part by said head for mounting said head both for sliding movement over and relative to said bed for individual, selective cooperation with said bed-sections and for preventing the displacement of said head in a direction normal to said bed, said head and each of said bed-sections having recessed portions provided 10 therein to define a forming chamber upon such cooperation, a die within said forming chamber, forming means mounted for slidable movement within the recessed portion of said head and also within the recessed portions of the bed-section between a first position where said forming means is positioned entirely within the recessed portion of said head and a second position where said forming means is positioned in part within the recessed portions of both said head and the bed-section associated therewith whereby said forming means cooperates with 15 said die to form a workpiece positioned thereon, means releasably securing said forming means in its first position, and pressure means effective on said forming means to release it from said securing means and move it to the second position and form the workpiece positioned 20 on said die.

25 3. In a forming apparatus the combination with a stationary continuous bed, of partitions dividing said bed into a plurality of aligned and individual bed-sections, a head, primary means for supporting said head on said bed for movement relative to said bed-sections and also for restraining said head from movement normal thereto, secondary means for also supporting said head on said bed for movement relative to and selective individual alignment with each of said bed-sections, a recess in each bed-section and in said head that combine to establish 30 a forming chamber when said head is aligned with each bed-section, a forming assembly slidably mounted in the recessed portion of said head and in both said recessed portions of said forming chamber when established as aforesaid, means for releasably securing said forming assembly in an inoperative position within the recessed portion of said head, and means for releasing said forming assembly and for operating said forming assembly 35 within said forming chamber.
